UNITED STATES PATENT OFFICE.

LLEWELYN J. DAVIES, OF CINCINNATI, OHIO.

VALVE-SPRING LIFTER.

1,393,669.

Specification of Letters Patent. Patented Oct. 11, 1921.

Application filed June 15, 1920. Serial No. 389,175.

To all whom it may concern:

Be it known that I, LLEWELYN J. DAVIES, a citizen of the United States, residing at Cincinnati, in the county of Hamilton and 5 State of Ohio, have invented certain new and useful Improvements in Valve-Spring Lifters, of which the following is a specification.

This invention relates to an improved valve spring lifter of the general character 10 disclosed in Patent No. 1,311,805, issued to me July 29, 1919, and has as one of its principal objects to provide a device where- in the operation of lifting a valve spring may be speedily accomplished.

15 The invention has as a further object to provide a valve spring lifter employing a rigid fulcrum bar for the lifting lever of the device and wherein said bar will be formed to support the lever either close to 20 the stock of the bar or spaced therefrom in order that the fulcrum point of the lever may be maintained close to the working end thereof regardless of the position of adjustment of the bar.

25 And the invention has as a still further object to provide a device of this character which may be readily adjusted to suit the requirements of different engines and will thus be adapted for general use.

30 Other and incidental objects will appear hereinafter:

In the drawings:

Figure 1 is a side elevation showing my improved device in connection with an internal combustion engine of conventional design,

Fig. 2 is a view similar to Fig. 1, showing the device in connection with a slightly different design of engine,

40 Fig. 3 is a perspective view showing the supporting bracket and fulcrum bar of the device in detail,

Fig. 4 is a fragmentary sectional view showing the mounting of the spring engaging jaws upon the lifting lever of the device,

45 Fig. 5 is a fragmentary sectional view taken at substantially right angles to Fig. 4,

Fig. 6 is a detail section showing the mounting of the handle upon the lifting lever, and

Fig. 7 is a fragmentary plan view showing a slightly modified form of lifting lever.

In carrying the invention into effect, I employ a body bar or lifting lever 10 which is provided at its forward end with a head 55 11 in the rear of which is a slot 12. Pivoted upon the head are jaws 13 provided at their lower edges with inwardly directed lateral flanges 14. These jaws are provided with mating ears 15 overlying the head at its 60 ends and extending through said ears and the head is a pivot pin 16 swingingly connecting the jaws with the head. Projecting rearwardly from the jaws are lugs 17 and

slidable within the slot 12 to engage between 65 these lugs is a wedge block 18. Threaded through the block is an adjusting screw 19 journaled at its inner end in the inner end

wall of said slot and fixed to the screw is an adjusting nut 20. Thus, this screw may 70 be operated for advancing the wedge block and swinging the jaws toward each other.

On the other hand, by retracting the wedge block, the jaws will be permitted to swing 75 away from each other and normally acting

to spread the jaws is a spring 21 lying between and bearing at its ends against the inner sides of the jaws, the spring being carried by suitable centering pins upon the 80 jaws. At its outer end portion the lever 10

is reduced and slidable thereon is a tubular handle 22 held against outward displacement by a pin 23 engaged through the lever, the handle being contracted at its inner end,

as particularly shown in Fig. 6, to coact with 85 said pin. As will be perceived, the handle may be shifted outwardly upon the lever for increasing the effective length thereof.

Formed in the lower edge of the lever at its forward end portion is a series of notches 24. 90 Associated with the lifting lever is a fulcrum bar 25 provided at its lower end with a laterally curved arm 26, the outer end portion of which is deflected to one side out of the plane of the bar. Formed on the 95 outer end of said bar is an upstanding fork 27. Coacting with the fulcrum bar is a supporting bracket 28 provided at its forward end with a depending hook 29. As will be observed, the fulcrum bar is preferably 100

round while the supporting bracket is flat and slidably connecting these elements is a substantially channel shaped coupling sleeve 30. The bar 25 is freely engaged 5 through suitable registering openings in the side flanges of this sleeve while the supporting bracket is slidably fitted through the sleeve behind said bar and threaded through the sleeve to coact with the bracket is a 10 clamping screw 31. As will be clear, this screw may be operated to bind the bracket against the fulcrum bar and consequently lock both the bracket and bar in adjusted position upon the bracket.

In Fig. 1 of the drawings, I have shown 15 my improved valve spring lifter in connection with an internal combustion engine 32 of conventional design. The stem of one of the valves of the engine is indicated at 33 and the usual spring about the stem at 34. As is 20 well known, this spring is retained by a pin engaged through the stem at the lower end of the spring. Formed in the engine above the valve is the customary orifice 35. In 25 the use of my improved device, the hook 29 of the supporting bracket 28 is engaged in the orifice 35 of the engine when the sleeve 31 is adjusted along the bracket so as to bring the fulcrum bar 25 up close to the 30 engine head. Coincidentally, the fulcrum bar is adjusted longitudinally through the bracket so as to dispose its arms 26 at the desired elevation relative to the lower end 35 of the spring 34. The jaws 13 upon the lifting lever 10 of the device are then, in the manner previously indicated, adjusted so that the flanges 14 of said jaws may be engaged beneath the spring when the lever is arranged to extend across the arm of the 40 fulcrum bar, the arm engaging an adjacent one of the series of notches 24. As will be readily understood, the lever 10 may then be rocked upon the arm of the fulcrum bar for lifting the valve spring so that the pin 45 through the valve stem at the lower end of said spring may be readily removed.

In Fig. 2, I have shown my improved device in connection with an engine of slightly different design. In this figure, the engine 50 is conventionally illustrated at 36 and projecting from the engine head is one of the manifolds 37. The stem of one of the valves of the engine is indicated at 38 while the spring about this valve stem is indicated 55 at 39. As will be noted, the presence of the manifold 37 makes it impossible to position the fulcrum bar 25 in closer to the engine head, as illustrated in Fig. 1. The supporting bracket 28 is accordingly engaged 60 against the upper side of the manifold and in order to bring the fulcrum point of the lifting lever in as closely as possible to the inner end of the lever, the fulcrum bar is arranged to abut the manifold while the 65 arm 26 of said bar is disposed to project

inwardly beneath the manifold. The jaws of the lifting lever are then engaged beneath the valve spring 39 when the lever is rested at its lower edge within the fork 27 of said arm so that the lever may be 70 rocked for lifting the spring. It will accordingly be seen that I provide a highly effective construction and a device which may be quickly and easily manipulated. By adjusting the jaws of the lifting lever, these 75 jaws may be readily engaged beneath valve springs of different diameters. Further, by adjusting the fulcrum bar relative to the supporting bracket therefore, the effective length of the bar may be readily varied while 80 by adjusting the supporting bracket with respect to the bar, the effective length of this bracket may be varied. The device may accordingly be manipulated to meet the varying requirements of different engines 85 and is, therefore, adapted for a wide range of use.

In Fig. 7 of the drawings, I have illustrated a slightly modified form of lifting lever. In this modification, the lever 90 is formed of sections, the innermost of which is indicated at 40 while the outer section is indicated at 41. The inner section carries the jaws 13 as in the preferred construction while the outer section carries the handle 22. At its outer end portion, the inner section is offset and the meeting ends of these sections are provided with mating annular heads 42 which are formed with coacting ratchet teeth. Through said head 100 is engaged a pivot pin 43 and adjustable upon this pin is a wing nut 44. As will be seen, this construction provides an arrangement whereby the outer section of the lever may be swingingly adjusted upon the inner 105 section thereof and locked in adjusted position, this feature allowing the outer section of the lever to be so arranged as to avoid any obstructing part of a vehicle or engine.

Having thus described the invention, what is claimed as new is:

1. A valve spring lifter including a fulcrum bar, a coupling sleeve slidably receiving the bar, a supporting bracket for the bar slidably engaged with said sleeve at one 111 side of the bar, means carried by the sleeve to coact with the bracket for locking both the bracket and bar fixed upon the sleeve, and lifting means adapted to be rocked upon said bar.

2. A valve spring lifter including a fulcrum bar provided with a laterally directed arm deflected at its outer end portion to one side of the plane of the bar and formed with a fork, a supporting bracket for the bar, and valve lifting means adapted to rock in said fork.

3. A valve spring lifter including a lever, valve spring engaging means carried thereby, a stop pin carried by the lever, a handle for 1

the lever slidable thereon to a position for increasing the effective length of the lever limited by said pin, and means for sustaining the lever whereby said lever may be 5 rocked.

4. A valve spring lifter including a sectional lever, means pivotally connecting the lever sections and comprising an element ad-

justable for locking the sections against relative movement, valve spring engaging means 10 carried by the lever, and means for sustaining the lever whereby said lever may be rocked.

In testimony whereof I affix my signature.

LLEWELYN J. DAVIES. [L.S.]
